UNITED STATES PATENT OFFICE.

JAMES R. HARMAN, OF PORT ANGELES, WASHINGTON.

EGG-CARTON.

1,321,740.

Specification of Letters Patent. Patented Nov. 11, 1919.

Application filed April 5, 1919. Serial No. 287,914.

To all whom it may concern:

Be it known that I, JAMES R. HARMAN, a citizen of the United States, residing at Post-Office Building, Oak street, Port Angeles, in the county of Clallam and State of Washington, have invented certain new and useful Improvements in Egg-Cartons, of which the following is a specification.

This invention relates to improvements in 10 cartons or containers used in carrying or transporting fragile articles, such as eggs.

The main object of the invention is to provide a carton which may be stamped from a single sheet of suitable material and 15 bent into shape for the purpose of holding a given number of fragile articles in spaced relation.

A further object is to provide a tubular container formed of a curved or rolled sheet 20 and having tongues bent from the material of the sheet to form partitions between the cells of the container. The construction is such that the bending of the tongues to provide the partitions will also furnish diamet- 25 rically opposite apertures, which will facilitate inspection of the contents of the receptacle or will permit candling of eggs contained in the packing without removing the eggs from said container.

30 With my novel carton a given number of eggs, say one-half dozen, may be placed in the package and tongues cut from the blank from which the carton is made, will form partitions between the eggs and prevent 35 the same from contacting. By my construction eggs may be shipped from the henry to the consumer without liability of break- 40 age and after the eggs are removed, the carton blank may be returned to the henry in flat form.

With the foregoing objects outlined and with other objects in view, which will appear as the description proceeds, the invention consists in the novel features herein- 45 after described in detail, illustrated in the accompanying drawing and more particu- larly pointed out in the appended claim.

Referring to the accompanying drawing:-

50 Figure 1 is a plan view of the blank from which the carton is formed.

Fig. 2 is a longitudinal vertical sectional view of the carton.

Fig. 3 is a perspective view, partly broken 55 away, of the same.

In the drawing, 1 designates the sheet

or blank from which the carton is formed. This blank may be made from any suitable material, but it is preferably formed of fibrous material, such as pasteboard. The 60 blank is provided with a series of pairs of tongues 2 which are spaced from each other and from the side edges 3 of the blank. These tongues are bent at angles to the blank as shown in Figs. 2 and 3, to form parti- 65 tions 4, which extend substantially radially across the carton 5 that is formed from the blank 1. As shown in Fig. 2, the partitions space the fragile articles 6 apart and prevent the same from contacting with one an- 70 other. The bending of the tongues out of alinement with the blank provides the apertures 7, which when the carton is formed, are arranged in diametrically opposite pairs, so that the eggs, if eggs are wrapped in the 75 carton, may be candled without removing the same from the receptacle.

The blank is provided with two parallel slits 8 which extend in from one of the edges 3 to form a tongue 9 arranged intermediate 80 the ends 10 of the blank. The opposite side of the blank is provided with a slot 11 de- 85 signed to receive the tongue 9, when the carton is formed, for the purpose of holding the carton in formed condition.

The ends of the blank are provided with flexible fastening devices 12, preferably formed of bendable metal, and secured to the blank by means of tongues 13. Parallel slits 14 are provided near the ends of the 90 blank and the carton, in formed condition, has its side edges additionally secured together by the fastening devices 12. These fastening devices extend across the interior of the carton, at angles to the partitions 4, 95 and their free ends are passed through the registering slits 14 and bent down as shown at 15.

In using the blank 1, the tongues 2 are bent up at right angles to the main portion 100 of the blank and the edges 3 are raised upwardly to bring the tongues into overlapping relation to form the partitions 4. Then the articles 6 are placed in the cells formed by said partitions. The tongue 9 is then 105 passed through the slit 11 and finally the fastening strips 12 are inserted through the registering apertures 14 and bent down upon the top of the carton. The carton is then in the condition shown in Figs. 2 and 3, in 110 which condition it is ready to be handled or shipped.

When the articles are removed from the carton, the carton may be opened into flap shape and it can then be shipped flat.

Having now described my improved carton and the blank from which it is formed, I wish to state that I am aware that various changes may be made in the structure without departing from the spirit of the invention, as set forth in the claim.

10 What I claim and desire to secure by Letters Patent is:—

A carton formed from a single rectangular sheet of flexible fibrous material having two parallel series of spaced tongues cut 15 from the material, said sheet being rolled

into tubular form and said tongues being bent to cross the interior of the tube and form spaced partitions, a tongue provided at one edge of the sheet, said sheet having a slit near its opposite edge to receive the last 20 named tongue, said sheet also having a plurality of aligned slits located near each end of the same, and flexible metallic strips permanently secured to the intermediate portions of the ends of said sheet and passing 25 through the last named slits for securing the opposite side edges of the sheet together.

In testimony whereof I affix my signature.

JAMES R. HARMAN.
